Des. 233,390
Patented Oct. 29, 1974

233,390

DISPLAY CASE FOR COINS OR THE LIKE

Fred Povitz, 5519 Cavendish St., Cote St. Luc,
Montreal, Quebec, Canada

Filed June 20, 1972, Ser. No. 264,575

Claims priority, application Canada May 9, 1972

Term of patent 14 years

Int. Cl. D20—02

U.S. Cl. D6—173

FIG. 1.

FIG. 2.

FIG. 3.

FIG. 4.

FIG. 5.

FIG. 6.

FIG. 7.

FIG. 1 is a perspective view of a display case, showing my new design in opened condition;

FIG. 2 is a right side elevational view thereof;

FIG. 3 is a front elevational view;

FIG. 4 is a rear elevational view;

FIG. 5 is a top plan view shown in a closed condition;

FIG. 6 is a right side elevational view thereof; and

FIG. 7 is a bottom plan view.

I claim:

The ornamental design for a display case for coins or the like, as shown and described.
